UNITED STATES PATENT OFFICE.

FRANK J. DULTMEIER, OF DES MOINES, IOWA, ASSIGNOR TO DULCO MANUFACTURING COMPANY, A CORPORATION OF IOWA.

TUB STAND.

Application filed November 8, 1926. Serial No. 147,095.

My invention relates to stands of the kind used for tubs particularly in home laundries.

It is my purpose to provide a stand of this kind of simple and durable construction.

5 It is a special object of the present invention to provide a tub stand, which is economical to manufacture and can be sold at a moderate price.

Another purpose is to provide such a stand 10 having parts so constructed and arranged that a tub may be readily and easily mounted on and between the upper ends of the legs of the stand, and the legs may then be drawn together for causing them to grip and hold the 15 tub.

Another object is to provide in such a tub stand, a strong rigid leg structure combined with a suitable castor support.

With these and other objects in view, my invention consists in the construction, arrangement and combination of the various parts of 20 my tub stand, whereby the objects contemplated are attained, as hereinafter more fully set forth, pointed out in my claims, and illustrated in the accompanying drawings, in which:

Figure 1 is a side elevation of a tub stand embodying my invention, having a tub supported thereon.

30 Figure 2 is a top or plan view of the stand.

Figure 3 is a vertical, sectional view through a portion of the tub and one of the legs, taken on the line 3—3 of Figure 1, and illustrating the construction of one of the 35 castor holders; and

Figure 4 is a sectional view taken on the line 4—4 of Figure 3.

In the accompanying drawings, I have used the reference numeral 10 to indicate generally 40 a metal tub of the type which can be conveniently used with my improved tub stand.

I preferably provide the tub with an opening 11 in its bottom. Connected therewith is a piece of flexible rubber hose or the like 45 12. At the free end of the hose there is provided a clamp 13 to which is pivoted a hook 14 adapted to engage over the upper edge of the tub 10.

At the end of the hose is inserted a nipple 50 or sleeve 15 to prevent the collapse of the hose when the clamp 13 is fastened thereon.

For preventing water from flowing out of the hose when the clothes are put into the tub,

I preferably connect a cork 16 or other closure member by means of a small chain or the like 55 17 to the clamp 13 for closing the nipple 15.

My improved tub stand comprises a plurality of legs 18, preferably three in number, arranged in triangular spaced relation and tilted from their lower ends slightly inwardly toward each other at their upper ends. 60 Each leg preferably comprises an inwardly opening angle bar. The legs may be braced, fastened together and held in spaced relation by means of flat brace bars 19 illustrated in 65 Figures 1 and 2. These brace bars are bent at the ends to fit snugly against the flanges of the legs, as perhaps best illustrated in Figure 2.

The brace bars have enough width to permit the use of two rivets or bolts 20 one above the other for fastening each brace to each leg and on account of the bend at 21 in each brace, there is afforded a very strong rigid structure.

At their upper ends, the inner portions of the flanges of the legs 18 are notched out as at 22 to receive and support the bottom of the tub, as shown in Figures 2 and 3.

For holding the upper ends of the legs together and drawing them tightly against the tub for gripping the tub, and for accomplishing these purposes quickly and easily and imposing a uniform pull on the legs, I provide the following means:

Mounted in two of the legs close to their upper ends are eye-bolts 23, having their eyes on the inner sides of the legs and nuts 24 at their outer ends.

In the other leg is a similar eye-bolt 25, 90 similarly assembled and having on its outer end the wing nut 26.

A flexible cable of wire or the like 27 is secured to the eye of the eye-bolt 25 and thence extended through the eyes of the eye-bolts 23, 95 and is then fastened at its other end to the eye-bolt 25. The wing nut 26 is loosened until the legs at their upper ends can be readily spread sufficiently to receive the bottom of the tub.

It will be understood that there is sufficient 100 spring in the material to permit this action of the legs.

When the tub is seated on the legs as shown in Figures 1 and 3, the wing nut 26 is then tightened on the eye-bolt 25 for putting the 105 flexible member 27 under tension, and simul-

taneously drawing the upper ends of the legs toward each other for thus tightly gripping between them the bottom of the tub.

It will be seen that the legs are thus tightened against the tub by one operation of screwing on the wing nut 26, and that the inward pull on the three legs is equalized.

The tub will then be held firmly gripped between the legs and on account of the fact that tubs of this type ordinarily have a slight circumferential rib 27^a at the bottom, it will be seen that any accidental releasing of the tub is prevented.

It is desirable to provide a stand of this kind with castors and on account of the angle iron construction of the legs together with their inclined arrangement, the connecting of the castors with the legs involves a problem, which I have solved in the following manner:

20 The legs 18 are formed with notches 28 in their flanges opposite each other near the lower ends of the legs. For each leg, I provide a castor holder, comprising an angle fitting 29 adapted to receive the lower, outer part of the leg, and provided with projecting bendable fingers 30, which are adapted to be bent around the edges of the leg and to be received in the respective notches 28.

30 The angle fitting 29, is, of course, inclined parallel with the leg 18 in each case and for receiving and holding the castor in upright position is provided with upper and lower spaced, horizontal, outwardly projecting flanges 31 and 32 formed with registering holes 33 and 34. These holes receive the shank 35 of an ordinary castor wheel 36.

It will thus be seen that I have provided a tub stand, which can be manufactured at a minimum expense.

40 Where the braces 19 are fastened to the legs by bolts and nuts, the tub stand can be easily shipped or stored in knock-down form.

It is easy to set up and assemble, and little difficulty is involved in mounting the tub on the stand and fastening it rigidly thereto.

It will be understood from the foregoing that changes may be made in the details of the construction and arrangement of the parts

of my improved tub stand and it is my intention to cover by my claims, any modified forms of structure or use of mechanical equivalents, which may be reasonably included within their scope.

It may be suggested that the legs may be made in a single length in standard sizes in the factory for various sizes of tubs, and used with braces 19 and cables 27 of different lengths.

Similarly, the same braces 19 may be used with legs 18 of different lengths for providing stands of different heights.

This is of some importance on account of the variation in sizes of the tubs.

The shape and construction of the upper ends of the legs might be varied and still utilize my idea. For example, the legs may be notched out as at 22, leaving the upstanding part 22^a, or an extra piece may be used to serve the purpose of the part 22^a. This part 22^a is of some importance. Since the legs 22 are inclined inwardly from their bottoms to their tops, the parts 22 slightly overhang the rib 27^a for causing a real interlocking connection between the tub and stand.

The arrangement of the braces 19 with the bends 21 tends to take much of the strain that would otherwise be put on the bolt 20.

I claim as my invention:

1. In a tub stand, a plurality of legs, braces for holding them in spaced relation, a flexible member connected with the upper end of one leg, having a slidable connection with the upper ends of the other legs, a tub supported on and between the legs, and means for tightening the flexible member for causing the legs to grip the tub.

2. In a structure of the class described, the combination of a tub stand, having a plurality of legs, braces connecting and holding the legs in spaced relation, a tub supported between the upper ends of the legs, and means for simultaneously drawing the legs inwardly at their upper ends for gripping the tub.

Des Moines, Iowa, October 27, 1926.

FRANK J. DULTMEIER.
